UNITED STATES PATENT OFFICE

RAYMOND P. LANSING, OF MONTCLAIR, NEW JERSEY, ASSIGNOR TO ECLIPSE MACHINE COMPANY, OF ELMIRA, NEW YORK, A CORPORATION OF NEW YORK

ENGINE STARTER

Application filed May 14, 1927. Serial No. 191,342.

My invention relates to engine starting apparatus for the starting of engines such as internal combustion engines, more particularly but not necessarily airplane engines, and the object thereof is to provide a simple, efficient and reliable apparatus capable of either manual or power operation or both, and including an inertia means such as a flywheel which is actuated by such power or 5 manual means for the accumulation and storing of energy which is thereupon utilized by the application thereof to the engine at the will of the operator for cranking such engine, and characterized by provision of a low 10 speed high torque motor in place of the usual high speed low torque motor commonly employed in engine starters of this kind, and by such construction and arrangement that both the motor and the manual means 15 actuate the flywheel through the same speed multiplying means or gearing which in turn is utilized in thereafter transmitting through such gearing acting as reduction means the 20 energy of the flywheel through torque transmitting means including a driving member to the member of the engine to be started for the purpose of cranking the engine. My apparatus also preferably includes automatically 25 acting means for drivingly connecting the motor with the apparatus or gearing when the motor is energized and for automatically disconnecting the same therefrom at the end of the driving operation by the 30 motor and when the flywheel is delivering its energy to the engine and also when the 35 manual means is the actuating means of the apparatus and the flywheel is thereby being actuated. Other features of advantage and utility in the construction and functioning 40 of my apparatus will be apparent from the 45 description hereinafter given.

In the drawings, Figure 1 is a longitudinal sectional elevation of my apparatus complete;

Fig. 2 is a similar section of a portion thereof enlarged; and

Figs. 3 and 4 sections of portions of the apparatus illustrating modified forms of construction.

For the purpose of a clear and definite de-

scription of my invention and for convenience, I will describe the same as embodied in the constructions of apparatus herein illustrated of which Figs. 1 and 2 show the present preferred and recommended form, 55 although it will be understood that the same is not limited thereto but may partake of different forms and arrangements of embodiment.

My apparatus comprises a drive or transmission proper including a driving member adapted to engage and crank a member of the engine to be started, gearing which is speed multiplying gearing or reduction gearing according to whichever end thereof is the driver, an inertia means or flywheel, and power 60 means and manual means for actuating the flywheel through such gearing.

First describing the drive proper as herein illustrated, the same is located within a 70 main casing 1 which is suitably supported as by being detachably connected with the crankcase 2 of the engine in suitable manner as by means of the bolts 3, a small portion of which crankcase is illustrated. Within the 75 casing there rotates a driving barrel 4 and a control member or nut 5 located and operating concentrically therein and operatively connected with the barrel by a yielding driving connection which is here in the form of a 80 friction clutch 6. This clutch is composed of two sets of disks which are splined respectively to the interior of the barrel and to a right-hand extension of the nut, Fig. 1. The proper pressure for the disk is provided 85 by a series of springs 7 located within the barrel and such pressure is regulated by an adjustable ring 8 screwing into the interior of the barrel at the left-hand end thereof. The thrust of these springs is against the 90 flange 9 of the nut and tends to force such nut inwardly and consequently force the clutch disks against the spacing ring 10 and into frictional contact with each other.

The nut 5 has internal long lead threads 95 in which is threaded a screw shaft 11 constituting the main portion of the driving member whose other principal portion is a clutch member 12 adapted to engage a member of the engine to be started, such as the 100

corresponding clutch member 13 which may form a part of or be secured to any rotatable part of the engine such as the crank shaft 14 thereof. The member 12 has clutch jaws 15 adapted to engage complementary clutch jaws 16 on the engine member, which jaws are adapted to become automatically disengaged because of their inclination, when the engine starts on its own power. The clutch member 12 is splined to the outer end of the screw shaft 11 whereby such parts have a relative longitudinal movement of limited degree independent of each other.

The clutch member 12 is held in outward position and kept in place upon the shaft 11 with a yielding pressure in suitable manner as by means of a coil spring 17 which bears at its outer end against the bottom of the sleeve portion 18 of the driving member and at its inner end against the bottom of a socket 19 formed in the outer end of a screw shaft. The interior of this sleeve 18 has splines 20 whereby the same is splined to the shaft 11 as above stated. The outward movement of the member 12 is limited by a nut 21 screwing onto the outer or left-hand end of an operating rod 22 which passes centrally through the driving member and also through the reduction gearing and starting motor as herein-after explained. In the present instance this rod is manually operated and connected at its outer end which is extraneous to the motor with an operating link 23 which extends to some convenient location whereby it may be operated by the operator either directly or through other connections, not shown.

The driving barrel 4 has an end or bottom portion 24 which has a central bore to drivingly receive the smaller diameter portion 25 of a hub of a pinion hereinafter described, through which hub the rod 22 passes freely and on which certain members of the gearing are mounted. Upon such end portion 24 there is mounted a series of planetary pinions 26 by means of a ring 27 and studs 28. These pinions mesh respectively with a stationary internal gear 29 secured to the casing 1 in suitable manner as by means of screws 30 and with a central pinion 31 here formed on the hub itself of a large gear 32 which is mounted to rotate freely upon the hub 25 through the medium of the bearings 33.

The gearing further comprises a pinion 34 here formed on the hub itself of a large gear 35 and meshing with the gear 32. This gear 35 in turn is operatively connected with a pinion 36 formed as a part of the inertia means or flywheel.

The gearing described is located in a casing 1^a which is secured to the main casing in suitable manner as by means of the screws 37, and in opposite walls of such casing 1^a are mounted the bearings 38 and 39 for the shaft 40 on which the gear 35 is mounted either

loosely or by being secured thereto as may be desired.

Next referring to the inertia means the same here comprises a flywheel located in and rotatably supported by another casing 1^b which is secured to the casing 1^a in suitable manner as by means of the bolts 41. This casing 1^b has a downward extension 1^c which fits in the upper end of the casing 1^a. The flywheel is composed of a rim 42 having a predetermined or desired mass or weight, a web 43 and a central extending hub 44 which is mounted in the bearings 45-46 in the casing 1^b and extension 1^c and which is drivingly secured in suitable manner as by key 47 to the hub of the pinion 36.

Next describing the manually operated means, the same comprises a cranking shaft 48 rotatably mounted in one wall of still another casing 1^d which is secured to the casing 1^a in suitable manner as by means of the screws 49. The outer end of this cranking shaft is provided with suitable pins 50 which are adapted to be engaged by an ordinary hand crank applied thereto and rotated by the operator. The inner end of this cranking shaft is provided within the casing 1^d with a bevel gear 51 which meshes with a corresponding bevel gear 52 the larger diameter portion 53 of whose hub is mounted in the bearings 54 in one of the walls of the casing 1^a and held in position by the lock nut 55. Referring to the starting motor which is indicated generally at 56 the same is detachably secured to the casing 1^d in suitable manner as by means of the screws 57. This motor which is of the low speed high torque type and preferably series wound has an armature shaft 58 having a central bore through which the rod 22 loosely passes and being extended and preferably supported towards its outer end in bearings 59 which are located in a cylindrical extension 60 secured to the frame of the motor by the screws 61.

The automatic operating connections between the motor and the gearing here comprise a nut 62 which is threaded upon the threads 63 at the outer end of the armature shaft whereby when such shaft is rotated this nut will automatically move or advance outwardly towards the left. This nut is provided with clutch jaws 64 adapted to engage corresponding clutch jaws 65 formed on the inner or right-hand face of the bevel pinion 52. The described advance movement of the nut 62 is against the tension of a light spring 66 bearing thereagainst, and against a spring abutment 67 secured to the outer end of the armature shaft.

Describing a cycle of operation, and beginning with the parts in the normal position shown in the drawings and with the starting motor as the actuating means, when the motor is energized the armature shaft will be rotated whereupon the nut 62 will ad-

vance outwardly to the left and engage the bevel pinion 52. The torque of the armature will thereupon be transmitted to the pinion 52, plate 24, planetary gearing, and gear 32 and thence to the gear 35 and finally to the flywheel 42 through the pinion 36. The starting motor is a slow speed high torque motor, as stated, and the torque being transmitted through the gearing in a direction to the flywheel such gearing will be speed multiplying gearing and the speed of the motor will thereby be multiplied and the flywheel will be rapidly rotated.

When the desired speed of rotation of the flywheel is attained the current to the motor may or may not be interrupted as desired, but the rod 22 is moved longitudinally to the left by the operator thereby causing the screw shaft 11 and its clutch member 12 to be likewise moved to the left through such longitudinal movement and the screw threaded connection of such shaft with the nut 5, whereupon the clutch jaws 15 and 16 will engage and the engine will be rotated and thereby cranked by the stored up energy of the rapidly rotating flywheel 42. This energy is transmitted through the gearing now acting as reduction gearing, that is, through the gears 35 and 32 to the planetary gearing and thence to the driving barrel 4 and from such barrel through the clutch 6 to the nut 5 and screw shaft 11 and clutch member 12 and finally to the engine as described. The screw threaded connection between the shaft 11 and its nut 5 assures full engagement of the clutch jaws and maintains the same during the driving operation.

When the engine starts on its power, the driving member 11-12 will be automatically disengaged from the engine member, both by the action of the inclined jaws 15-16 and the screw thread connection between the shaft 13 and its nut 5. It is obvious that the motor may be kept energized during the starting operation but in practice it is sufficient to cut off the current supply to the motor as soon as the desired speed of rotation of the flywheel is reached and rod 22 has been actuated. When the motor is thus de-energized and the gearing becomes the driver the nut 62 is automatically disconnected and restored to the normal position shown assisted by the light spring 66.

When the manual means is employed, the operator cranks the shaft 48 whereupon the pinion 52 will be rotated together with the gearing and the flywheel in the same manner as performed by the starting motor. When the flywheel has reached the desired or predetermined speed the apparatus is operated in the same manner as already explained. It will be noted that during the manual operation the starting motor is disconnected and the only load to the hand cranking is the load of rotating the flywheel.

In Fig. 3, I have shown the modified form of construction which is characterized by the arrangement of the electric motor in a position at right angles to that illustrated in Figs. 1 and 2 and with the armature shaft in line with the cranking shaft of the manual means and further characterized by the actuation of the driven bevel gear 52 by a bevel gear similar to the manually operated gear 51, it being understood, of course, that in order to retain the same direction of engine cranking, the hand cranking should be backwards as compared with usual direction, although if desired, the motor itself may be made to run in a direction opposite to that of the motor of Figs. 1 and 2.

Referring to Fig. 3, the parts corresponding to those shown in Figs. 1 and 2 are given the same reference numerals. In this modification, the clutch jaw 65 instead of being upon or a part of the gear 52 is connected with or as herein shown forms a part of a shaft 68 and has its bearings in a casing 1^a which is secured to the casing 1^a and to the motor frame and also serves as the mounting for the manually operated means. At the inner end of this shaft 68 there is drivingly secured a bevel pinion 69 which meshes with the bevel gear 52, this shaft 68 and the cranking shaft 48 being in axial alinement and meshing with the gear 52 at diametrically opposite points. In this construction, the manually operated rod 22 extends between the ends of the two shafts 48 and 68 and extraneous of the casing 1^a. The mode of operation is the same as that above described with the exception of course that the automatically operating clutch member 62 does not clutch the gear 52, but becomes automatically connected with the shaft 68 through whose rotation the bevel pinion 69 and consequently the remainder of the mechanism are operated.

Referring to the modification illustrated in Fig. 4, a common cranking shaft is employed for a single bevel pinion which meshes with the gear 52, the motor armature and the manual cranking shaft which now becomes a common cranking shaft being in axial alinement. According to this construction, the common shaft is a shaft 70 having its bearings in a casing 1^b and having intermediate its length and drivingly secured thereto a bevel pinion 71. One end of this shaft extends extraneous of this casing for the application of a hand crank as in Figs. 1, 2 and 3 while the other end of such shaft is formed as or provided with a clutch member 72 similar to the clutch member 65 and adapted to be drivingly connected with a clutch member such as the member 62 and driven by the motor as illustrated in Fig. 3. The manually operated rod 22 is obviously curved around such cranking shaft as indicated in the drawing. The mode of operation is the same as that above described.

For practical purposes, the electric motor may have a normal end point of say 100 R. P. M. prior to engine engagement and as the gear ratio here shown is about 150 to 1, it follows that the flywheel will be accelerated to a speed of 15,000 R. P. M. If a higher flywheel speed is desired, the same can be obtained by either increasing the gear ratio or modifying the motor to operate at a higher normal speed. Inasmuch as the motor is series wound and starts under no load, its initial acceleration is considerable which, assisted by the inertia of the nut 62, causes engagement with the gear 52.

It will be understood that the gearing above described is speed multiplying means when the torque is transmitted in a direction towards the flywheel and that it is speed reducing means when the torque is transmitted from the flywheel or inertia means to the driving member and thence to the engine, but for convenience, I will refer to such means in the claims as speed multiplying means.

By means of my apparatus I am enabled to employ a low speed high torque motor and to utilize the same gearing to multiply the speed of rotation that is utilized by the manual means.

In the present apparatus, there are employed certain constructions and features (such as the drive proper and the manual control of its driving member, the speed multiplying mechanism for the most part and the actuation by either or both manual means or power means), which are described and claimed in certain of my prior patent applications, such as those filed on September 28, 1925, Serial No. 59,113 and 59,114, and therefore I do not claim herein anything in common with such applications but the particular invention defined by the claims herein.

I claim:

1. An engine starter including torque transmitting means having a driving member adapted to engage and crank a member of the engine to be started, an inertia means, a low speed high torque electric motor, and a train of speed multiplying means, opposite ends of which train cooperates with the inertia means and motor respectively, said torque transmitting means being operatively connected with said train.

2. An engine starter including torque transmitting means having a driving member adapted to engage and crank a member of the engine to be started, an inertia means, a low speed high torque electric motor, and a train of speed multiplying means, opposite ends of which train cooperate with the inertia means and motor respectively, and an intermediate portion with the torque transmitting means.

3. An engine starter including torque transmitting means having a driving member adapted to engage and crank a member of the

engine to be started, an inertia means, a low speed high torque electric motor, and a train of speed multiplying means, opposite ends of which train cooperates with the inertia means and motor respectively, said torque transmitting means being operatively connected with said train, the armature shaft of the motor being in axial alinement with the driving member and means for controlling engagement of said driving member with said engine member extending through said armature shaft and the driving member and operatively connected with the latter.

4. An engine starter including torque transmitting means having a driving member adapted to engage and crank a member of the engine to be started, an inertia means, a low speed high torque electric motor, and a train of speed multiplying means, opposite ends of which train cooperate with the inertia means and motor respectively, said torque transmitting means being operatively connected with said train, said motor being normally disconnected from the speed multiplying means.

5. An engine starter including torque transmitting means having a driving member adapted to engage and crank a member of the engine to be started, an inertia means, a low speed high torque electric motor, and a train of speed multiplying means, opposite ends of which train cooperate with the inertia means and motor respectively, said torque transmitting means being operatively connected with said train, said motor being normally disconnected from the speed multiplying means, but adapted to be automatically connected therewith as an incident to the operation of such motor.

6. An engine starter including torque transmitting means having a driving member adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means.

7. An engine starter including torque transmitting means having a driving member adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means, said power means

being a low speed high torque electric motor.

8. An engine starter including torque transmitting means having a driving member adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means, said power means being normally disconnected from the speed multiplying means but adapted to be automatically connected therewith as an incident to the operation of such power means.

9. An engine starter including torque transmitting means having a driving member adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means, said power means being normally disconnected from the speed multiplying means but adapted to be automatically connected therewith as an incident to the operation of such power means, and said manually operated means being constantly connected with the speed multiplying means.

10. An engine starter including torque transmitting means having a driving member adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means, said speed multiplying means comprising a train of gearing, one end of which train is connected with the inertia means and the other end with said manually operated means and power means, whereby the speeds of the manual means and the power means are multiplied.

11. An engine starter including torque transmitting means having a driving member adapted to engage and crank a member of the engine to be started, an inertia means, manually operated means and power means, and speed multiplying means operatively connected with the torque transmitting

means and connected with the inertia means and also with the manually operated means and the power means, both of said latter means being adapted to apply torque which is transmitted through the speed multiplying means to the inertia means, said power means being a low speed high torque electric motor and said speed multiplying means comprising a train of gearing, one end of which train is connected with the inertia means and the other end with said manually operated means and the motor.

12. An engine starter including torque transmitting means having a driving member adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means, said speed multiplying means comprising a train of gearing including a pinion at one end, said manual means and power means drivingly cooperating with said pinion, and said inertia means drivably and drivingly cooperating with the other end of such train.

13. An engine starter including torque transmitting means having a driving member adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means, said speed multiplying means comprising a train of gearing including a bevel pinion, said manual means including a corresponding bevel pinion meshing therewith, and said power means being adapted to operatively engage and rotate the first named pinion.

14. An engine starter including torque transmitting means having a driving member adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means, said speed multiplying means comprising a train of gearing including a bevel pinion, said manual

means including a corresponding bevel pinion meshing therewith, and said power means being an electric motor having an armature shaft adapted to operatively engage and rotate the first named pinion.

15. An engine starter including torque transmitting means having a driving member adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means, said speed multiplying means comprising a train of gearing including a bevel pinion, said manual means including a corresponding bevel pinion meshing therewith, and said power means being an electric motor having an armature shaft in axial alinement with the axis of the first named pinion and adapted to operatively engage and rotate the same.

16. An engine starter including torque transmitting means having a driving member adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means, said speed multiplying means comprising a train of gearing including a bevel pinion, said manual means including a corresponding bevel pinion meshing therewith, and said power means being an electric motor having an armature shaft adapted to operatively engage and rotate the first named pinion, said driving member, the first named pinion, and the armature shaft being in axial alinement.

17. An engine starter including torque transmitting means having a driving member adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means, said speed multiplying means comprising a train of gearing including a pinion, the manual means engaging the periphery of such pinion to drive it and the

power means being adapted to engage a face of such pinion to drive it.

18. An engine starter including torque transmitting means having a driving member adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means, said power means being an electric motor having an armature shaft in axial alinement with the driving member, and control means passing through such shaft and operatively connected with such member for controlling its engagement with the engine.

19. An engine starter including torque transmitting means having a driving member adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means, said power means being an electric motor having an armature shaft in axial alinement with the driving member, and a manually operated rod passing through such shaft and operatively connected with such member for controlling its engagement with the engine.

20. An engine starter including torque transmitting means having a driving member adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means, said speed multiplying means comprising a train of gearing including a bevel pinion, said manual means including a corresponding bevel pinion meshing therewith, and said power means being an electric motor having an armature shaft in axial alinement with the axis of the first named pinion and adapted to operatively engage and rotate the same, and control means for the driving member passing through said armature shaft and first named pinion and operatively connected with such driving

member for controlling its engagement with the engine.

21. An engine starter including torque transmitting means having a driving member adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means, said speed multiplying means comprising a train of gearing including a bevel pinion, said manual means including a corresponding bevel pinion meshing therewith, and said power means being an electric motor having an armature shaft in axial alignment with the axis of the first named pinion and adapted to operatively engage and rotate the same, and a manually operated rod passing through the armature shaft and first named pinion and operatively connected with such driving member for controlling its engagement with the engine.

22. An engine starter including torque transmitting means having a driving member adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means, said speed multiplying means comprising a train of gearing including at one end of such train a pinion with which the manual means and power means cooperate drivingly, said pinion having a hub supporting other members of such train, the inertia means being drivenly and drivingly connected with the other end of such train.

23. An engine starter including torque transmitting means having a driving member adapted to engage and crank a member of the engine to be started, an inertia means, manually operated means and power means and speed multiplying means operatively connected with the torque transmitting means and connected with the inertia means and also with the manually operated means and the power means, both of said latter means being adapted to apply torque which is transmitted through the speed multiplying means to the inertia means, said speed multiplying means comprising a train of gearing including at one end of such train a pinion with which the manual means and power means cooperate drivingly, said pinion having a hub drivingly engaging a member of said torque

transmitting means, and said train also including gears forming operating connections between said hub and said last named member and the inertia means.

24. An engine starter including torque transmitting means having a driving member adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means, said speed multiplying means comprising a train of gearing including at one end of such train a pinion with which the manual means and power means cooperate drivingly, said pinion having a hub drivingly engaging a member of said torque transmitting means, and said train also including planetary gears mounted upon said last named member and also including gearing mounted on said hub and between the planetary gears and the inertia means.

25. An engine starter including torque transmitting means having a driving member adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means, said speed multiplying means comprising a train of gearing with the same end of which the manual means and the power means drivingly cooperate.

26. An engine starter including torque transmitting means having a driving member adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means, said speed multiplying means comprising a train of gearing with the same end of which the manual means and the power means drivingly cooperate and said inertia means being a flywheel drivenly and drivingly cooperating with the other end of said train.

27. An engine starter including torque transmitting means having a driving mem-

- ber adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means, said speed multiplying means comprising a train of gearing with the same end of which the manual means and the power means drivingly cooperate and said inertia means being a flywheel drivenly and drivingly cooperating with the other end of said train, a member of said torque transmitting means being operatively connected with an intermediate portion of such train.
- 20 28. An engine starter including torque transmitting means having a driving member adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means, said manually operated means including a cranking shaft and said power means including an electric motor positioned with its armature shaft in axial alignment with said cranking shaft.
- 25 29. An engine starter including torque transmitting means having a driving member adapted to engage and crank a member of the engine to be started, an inertia means, manually operated means and power means, and speed multiplying means operatively connected with the torque transmitting means and connected with the inertia means and also with the manually operated means and the power means, both of said latter means being adapted to apply torque which is transmitted through the speed multiplying means to the inertia means, said manually operated means including a cranking shaft operatively connected with said speed multiplying means and said power means including an electric motor adapted to be drivingly connected with said cranking shaft.
- 30 35 55 In testimony whereof, I have subscribed my name.

RAYMOND P. LANSING.
